UNITED STATES PATENT OFFICE

HAROLD P. SLEEMAN, OF EAST LIVERPOOL, OHIO, ASSIGNOR TO THE R. THOMAS & SONS COMPANY, OF EAST LIVERPOOL, OHIO, A CORPORATION OF OHIO

APPARATUS FOR PROTECTING POWER-LINE INSULATORS

Application filed April 30, 1927. Serial No. 187,906.

My invention relates to method and apparatus for protecting power line insulators, and particularly multi-unit insulators.

My invention contemplates the protection 5 of the insulator against unequal voltage stresses on the several units by better voltage distribution over the insulator, the means employed for this purpose being such that it does not interfere with "live line" insulator 10 testing appliances.

My invention contemplates the protection of the insulator by providing both a voltage distributor and also an arc-over path, in parallel with the insulator, to protect the 15 latter against injury by flash-over. In such a combination, my invention contemplates the location of the distributor between the line-end of the arc-over path and the power line, so that on arc-over the arc plays not upon 20 the voltage distributor but upon the arc terminal.

Again my invention contemplates, in this combination, a voltage distributor of such construction that should an arc form thereon, 25 it is automatically led to the arc-over terminal.

My invention also contemplates, in this combination, the location of the voltage distributor closer to the insulator than the 30 terminal at the line-end of the arc-over path, so that on arc-over the arc forms at a point more remote from the insulator than the voltage distributor.

From the standpoint of apparatus my invention 35 contemplates a combined arc terminal and voltage distributor, the latter preferably in the form of arcuate lateral extensions of the terminal and extending line-ward from the terminal, and inward toward 40 the insulator. A pair of such combined arc terminals and voltage distributors, when installed at the line-end of a multi-unit insulator, is so located that the arc-over terminals overlie the line conductor, while the 45 arcuate terminal extensions which constitute the voltage distributors, substantially surround the lower portion of the insulator but are so spaced at their adjacent ends as to permit the introduction of "live line" testing 50 appliances to the insulator.

Other features of my invention will be understood from the following description, or from the accompanying drawings, in which

Fig. 1 is a broken side elevation of a multi-unit suspension insulator to which are applied protecting devices which embody my invention in one form; 55

Fig. 2 is a plan view thereof;

Fig. 3 is an enlarged plan view of a combined arcing terminal and voltage distributor; 60

Fig. 4 is a side elevation thereof;

Fig. 5 is a front elevation thereof;

Fig. 6 is a section on the line 6—6, Fig. 3; 65

Fig. 7 is a section on the line 7—7, Fig. 3; and

Fig. 8 is a section on the line 8—8, Fig. 3.

It has been recognized (see Marvin 1,245,940) that in multi-unit insulators the voltage stresses upon the several units of the insulator are unequal, and that the voltage stress upon the units at the line end of the insulator materially exceeds that impressed upon the units at the opposite or 75 ground end of the insulator. As a result of this condition, failure of the insulator by puncture occurs most frequently in the units adjacent the line. The introduction of metal discs of various dimensions between the 80 several units of the insulator to vary their capacities, effects a voltage distribution which renders more uniform the stresses on the several units. But this manner of accomplishing the desired end is objectionable 85 since it increases the likelihood of flash-over on the insulator surfaces (by reason of the reduction of the leakage path), and moreover tends to cause an arc to cascade from arcing horns into the insulator, thus increasing 90 the probability of damage thereto from the heat of the arc.

My invention accomplishes the desired voltage distribution over the insulator string by providing a source of line voltage substantially surrounding the line end of the insulator at a point spaced radially therefrom, the current from this source reaching the units remote from the line, and preventing 95 the concentration of voltage stress upon 100

the unit or units at the line-end of the insulator. This voltage distributor is of such construction that while substantially surrounding the lower portion of the insulator, 5 it permits safe access to the insulator for the application thereto of live line insulator testing appliances, such as are now commonly used for field test. Preferably my invention is embodied in a voltage distributor 10 which has combined therewith an arcing terminal, and the latter is preferably so located with respect to the voltage distributor that arc-over is invited not to the distributor but to the arcing terminal. Preferably, further, 15 this terminal is of such construction that the arc is caused automatically to move away from the insulator. Danger that the arc, after formation, will strike into the insulator, is thus minimized.

20 Referring to the accompanying drawings, I have indicated in Fig. 1 a multi-unit suspension insulator of the link or Hewlett type, comprising a string of insulator units 15, of which the lowest unit is connected by 25 adapter 16 and hanger 17 to the power line P, while the top unit of the string is connected by adapter 18 and hook 19 to a grounded tower or other supporting structure (not shown). Associated with the 30 hanger 17 and secured thereto by bolt 20, is a bar 21, the opposite ends 22 and 23 of which are angled upward and are pierced at suitable points to receive the bolts 24 by which the combined arcing terminals and voltage 35 distributors of my invention are attached thereto.

Each combined arcing terminal and voltage distributor comprises a shank 25 channeled to fit the bar end 22 or 23 and apertured to accommodate securing bolts 24. At its free end the shank 25 is enlarged to form a spoon-shaped arcing terminal having a spheroidal surface 26 which merges into a contracted tip 27. This terminal is 40 scribed and claimed in the copending application of H. B. Vincent Serial No. 184,987, patented April 12th, 1932, Patent No. 1,854,083 and insofar as it is claimed therein I make no claim to it here. This terminal 45 has the characteristics of a sphere or high speed gap at the area 26, and of a needle point gap at the tip 27. Upon arc-over, between one of these terminals and a cooperating terminal at the ground end of the insulator, the arc strikes the area 26 and automatically travels outward to the tip 27. The arc thus moves away from the insulator immediately after its formation, and the danger that the arc will strike into the insulator is 50 minimized. The spheroidal area 26 of the terminal is also thus protected against injury incident to the play of an arc thereon. Inasmuch as the rating of the gap is governed by the spacing of the line and ground 55 terminals at their adjacent spheroidal areas

26, the protection of the latter against injury is of great advantage in stabilizing the rating of the gap so that the latter may be set accurately for a given arc-over value, which is maintained in spite of repeated arc-overs.

Associated with the arcing terminal and extending from opposite sides thereof are arcuate wings 28 and 29 which form the voltage distributor element of the appliance. These wings join the terminal at a point removed from the crest of the spheroidal area 26 and preferably extend line-ward therefrom, so that they do not invite the arc to strike the distributor wings. The upward inclination of the wings automatically causes the arc, should one form on the distributor, to rise to the arcing terminal. The wings are also spaced radially from the insulator a less distance than the arcing terminal. They are located substantially at the level of the lowermost unit 15 of the insulator string, but their position will vary with the line voltage and the character of the units which compose the insulator. The location indicated in the drawings therefore is merely illustrative of a single appropriate location for the type of insulator used and at a given line voltage.

In cross section the wings 28 and 29 are 95 preferably arched on a rather long radius with their convex faces toward the gap. Corona formation on the distributor is thus minimized. A stiffening rib 30 may be provided on the concave face of each wing to 100 add to its rigidity.

It will be noted that between the ends of a pair of voltage distributors located as indicated in Fig. 2, a space 31 is afforded through which a live-line testing appliance 105 of a type well known in the art, may be passed into contact with the insulator units for testing the latter while in service. This is a feature of great practical value, since it enables the linemen to carry out tests without inconvenience or danger of establishing direct contact with a metal part at line voltage. Note that the arcing terminals overlie the power line. Consequently the space 31 through which the tester passes is located at a point remote from the line and in a plane substantially normal to the latter.

I have shown the voltage distributor applied only to the line end of the insulator, while at the ground end of the latter an arcing horn 32 is provided which, while having the characteristics of the terminal of the fitting at the line-end of the insulator, lacks the voltage distributor wings. If for any reason desired, however, the distributor fitting may be used at both ends of the insulator.

It will be understood further that the invention is not restricted in its utility to multi-unit insulators of the link or Hewlett type 130

illustrated in Figs. 1 and 2, but is equally applicable to insulators of the cap and pin type, or to multi-unit post insulators. I use the expression "multi-unit insulator" therefore in a sense broad enough to include any type of insulator in which the problem of voltage distribution is one of importance.

It will be understood furthermore that whether or not the voltage distributor has 10 associated therewith an arcing terminal of the type indicated, it possesses features of novelty and advantage which are not dependent upon the combined use therewith of an arcing terminal of the type shown. Certain 15 of the claims which point out my invention are not restricted to this combined structure.

The details of contour and arrangement of parts are subject to wide variation, while still embodying the thoughts which underlie 20 what I claim as my invention.

I claim—

1. A fitting for a multi-unit power-line insulator comprising arcuate conductors adapted to be connected to the line and extend 25 around the line-end of the insulator to form a voltage distributor, said conductors having associated arc-gap terminals whereby arcing over the surface of the insulator units is prevented.

30 2. A fitting for a multi-unit power-line insulator comprising arcuate conductors adapted to be connected to the line and extend around the line-end of the insulator, said conductors having associated arc-gap terminals spaced radially more remote from the 35 insulator than the voltage distributor.

3. A combined arc-gap terminal and voltage distributor for multi-unit power-line insulators, comprising a high speed gap terminal and a voltage distributor at one side 40 thereof, said distributor comprising arcuate extensions from said terminal.

4. A combined arc-gap terminal and voltage distributor for multi-unit power-line insulators, comprising a high speed gap terminal and associated arcuate voltage distributor extensions on opposite sides thereof, said 45 extensions having convex surfaces faced toward the gap.

50 5. A combined arc-gap terminal and voltage distributor for multi-unit power-line insulators, comprising a spoon-shaped gap terminal and voltage distributor wings extending from opposite sides of the terminal.

55 6. A combined arc-gap terminal and voltage distributor for multi-unit power-line insulators, comprising a spoon-shaped gap terminal and voltage distributor wings extending from opposite sides of the base of the 60 terminal.

65 7. A combined arc-gap terminal and voltage distributor for a multi-unit power-line insulator, comprising an element adapted for connection to a line support, together with a combined arc-gap terminal and voltage dis-

tributor adjustably connected to said support for varying the position of the distributor in the direction of the axis of the insulator.

8. In combination, a multi-unit power-line insulator, an arcing horn and a voltage distributor at the line end of said insulator and an arcing horn at the other end thereof, said arcing horns forming a gap spaced from said insulator.

In testimony whereof I have signed my name to this specification.

CERTIFICATE OF CORRECTION.

Patent No. 1,896,189.

February 7, 1933.

HAROLD P. SLEEMAN.

It is hereby certified that error appears in the printed specification of the above numbered patent requiring correction as follows: Page 3, line 33, claim 2, after "insulator" and before the comma, insert the words "to form a voltage distributor"; and that the said Letters Patent should be read with this correction therein that the same may conform to the record of the case in the Patent Office.

Signed and sealed this 9th day of May, A. D. 1933.

M. J. Moore
